(57) **CLAIM**

The ornamental design for a T-shirt and sleeves, as shown and described.

DESCRIPTION

FIG. 1 is a front elevational view of a T-shirt and sleeves, showing my new design, shown in an exploded condition;

FIG. 2 is a rear elevational view thereof;

FIG. 3 is top plan view thereof;

FIG. 4 is a bottom plan view thereof;

FIG. 5 is a right side elevational view thereof, shown in an assembled condition; and,

FIG. 6 is a left side elevational view thereof.

The broken lines shown in the drawings are for illustrative purposes only and form no part of the claimed design.
